UNITED STATES PATENT OFFICE.

FRED H. MASON, OF SCRANTON, PENNSYLVANIA.

COMBINED GLARE SHIELD, SIDE SHIELD, AND SIGNALING MEANS.

Application filed September 30, 1922. Serial No. 581,637.

To all whom it may concern:

Be it known that I, FRED H. MASON, a citizen of the United States, residing at Scranton, in the county of Lackawanna and State 5 of Pennsylvania, have invented certain new and useful Improvements in Combined Glare Shields, Side Shields, and Signaling Means; and I do hereby declare the following to be a full, clear, and exact description 10 of the invention, such as will enable others skilled in the art to which it appertains to make and use the same.

This invention relates to an attachment for automobiles, affording by means of an 15 improved and simplified structure, an auxiliary side windshield, a signal device and a glare shield.

The object of the invention is to provide a device of the character indicated which 20 will be easily applied, durable and readily manipulated. Further subordinate objects will more clearly appear in connection with the detailed description hereafter.

The invention consists in the novel construction, arrangement and combinations of parts as hereinafter fully described and claimed.

Three sheets of drawings accompany this specification as part thereof, in which like 30 reference characters indicate similar parts throughout.

Figure 1 is a side elevation of the improved device as applied to a car;

Fig. 2 is a front elevation of the device 35 applied;

Fig. 3 is a rear elevation;

Fig. 4 is a detail plan view of a clamping member;

Fig. 5 is a plan fragmentary view illustrating the mode of attaching the translucent plate to the holder;

Fig. 6 illustrates a modified form of attaching the device to a car;

Fig. 7 is a perspective rear view illustrating the mode of attaching the translucent member;

Fig. 8 is an end view taken from the top of Fig. 6;

Fig. 9 is a side view of the supporting 50 device attached to the windshield, the translucent member being removed;

Fig. 10 is a vertical transverse sectional view through Fig. 9, and

Fig. 11 embraces elevations of the three 55 principal parts of the supporting member.

In accordance with my present invention, a translucent plate 1 of amber or other suitably colored glass or similar material is resiliently supported as by a spring member 5 from a rotatable part removably mounted 60 to the side frame member S of the windshield of a car. Means are provided as will be hereinafter described, by means of which the plate 1 may be rotated to occupy a position with its long axis substantially parallel 65 with the plane of the windshield, but its short axis extending obliquely thereto, as is illustrated in Fig. 1, in which position the device operates as an auxiliary side windshield. The plate 1 may be further rotated 70 and automatically secured with its long axis oblique to the horizontal as is illustrated in Fig. 2, in which position its short axis will be inclined also obliquely to the horizontal, in which position it will operate very effectively and efficiently to shield the eyes of 75 the driver from the glare of headlights on a car approaching from the opposite direction. Means are further provided for a still further rotation of the device with its long 80 axis in a horizontal position, as is illustrated in Fig. 3, in which position suitable lettering provided adjacent one end of the plate indicates a signal to stop, for the benefit of following cars.

To support the fragile plate 1, substantially U-shaped clamps 2 are provided, each having one leg provided with offset lugs 4 and its other leg provided with a threaded and adjustable clamping member 3. A preferably flat spring member 5 is secured by its ends to the offset lugs 4 of the clamping members 2 as by bolts 6, and this spring member 5 is secured centrally as by screw 8 to a spindle 7 having one end provided 95 with a flat face 11' to provide a seat for the spring 5 and its other end squared as at 11 to provide a seat for an operating wheel 26 adapted to be secured thereto as by a screw 27. A transverse pin 9 is positioned transversely through spindle 7 adjacent the flattened end 11'.

A tubular guide member 12 is provided for the spindle 7 in which the latter is adapted to both slide and rotate. The tubular member 12 is provided on one end with a plurality of diametrically opposed notches 15 adapted to co-act with the transverse pin 9 in spindle 7. The tubular member 12 is further provided with an enlarged part 13 provided adjacent each end with the threads 14-14'. Supplementary tubular housing members 16 are provided, each having angularly disposed faces 17 adapted to seat a wrench and each being interiorly threaded adjacent one end as at 18, said threads adapted to co-act with threads 14-14' upon the tubular guide 12. Semi-cylindrical clamping members 19 are provided, each having an offset lug 20, said lugs 20 being provided with holes 21 adapted to receive and fit snugly upon the tubular guide 12 upon the large part 13 intermediate the threads 14-14', and when so assembled the semi-cylindrical parts 19 are adapted to co-act to embrace the side frame member S of the windshield as is well illustrated in Fig. 9. A compression spring 22 is provided to surround spindle 7 within one of the tubular members 16, one end of said spring abutting against an end of the tubular guide 12 and the other end of the spring abutting against a cap 23 screwed upon threads 10 provided on spindle 7 adjacent the squared end 11.

By pressing upon hand wheel 26, spindle 7 is forced against the compression of spring 22 through tubular guide 12, thus moving pin 9 from engagement with notches 15 whereupon spindle 7 may be rotated as desired. Upon the release of the outward pressure upon hand wheel 26, spring 22 will retract spindle 7, again bringing pin 9 into engagement with the then adjacent notches 15 to secure the device in adjusted position. If desired, the entire supporting device can be swung upon the frame S as a vertical axis if it is desired to modify the position of the device in a horizontal plane.

Where the frame of the windshield S' is of an irregular shape, a supplementary clamping member 24 may be provided being of a substantially U-shape, having the ends of its legs bent to conform to the configuration of the frame S', while the portion intermediate the legs is bent to embrace a cylindrical post 25 to which the device may be attached, as previously described. With this modified structure, the clamping members 19 may be advantageously combined into a one-piece clamp 19' bent into tubular form and having lugs 20' extending

from adjacent edges as is illustrated in Fig. 6, the holes 21' coinciding to receive the tubular guide 12.

Having thus fully described my invention, I claim:

1. In a device of the character described, a supporting device comprising a spindle, a tubular guide for the spindle, clamping means adapted to secure the tubular member to a support including complementary parts 70 slidable on the tubular guide, and housing members adapted to embrace the tubular guide to secure the clamping means.

2. In a device of the character described, a supporting device comprising a spindle, a tubular guide for the spindle, locking means to prevent the rotation of the spindle in the tubular guide, clamping means for securing the tubular guide to a support, housing members co-acting with the tubular guide to secure the clamping means and enclosing the locking means and means for unlocking the spindle and rotating the same in the tubular guide.

3. In a device of the character described, a supporting device comprising a spindle having a transverse pin, a tubular guide for the spindle, said tubular guide having one end provided with a plurality of diametrically disposed notches adapted to engage said transverse pin, said guide being further provided with spaced exterior threaded parts, clamping members having lugs provided with orifices adapted to receive the tubular guide and to seat thereon intermediate its threaded parts, tubular members each provided adjacent one end with interior threads adapted to co-mate with the threaded parts of the tubular guide, a compression coil spring adapted to surround 100 the spindle and seat against one end of the tubular guide within a tubular member and stop means carried by the spindle to operate against said compression spring.

4. In a device of the character described, a supporting device comprising a spindle provided with a transverse pin, a tubular guide for the spindle having one end transversely notched to receive said pin, tubular housing members adapted to embrace the tubular guide, clamping members slidable on the tubular guide and adapted to be secured thereon by the tubular housing members co-acting therewith, and a compression spring operative to maintain the spindle 110 with its transverse pin in engagement with the notched end of the tubular guide and all within said tubular housing members.

In testimony whereof I affix my signature.
FRED H. MASON.
